UNITED STATES PATENT OFFICE

ARTHUR J. SUNDLUN, OF WASHINGTON, DISTRICT OF COLUMBIA

DESIGN FOR A BUTTON OR SIMILAR ARTICLE

Application filed July 31, 1931. Serial No. 40,741. Term of patent 3½ years.

To all whom it may concern:

Be it known that I, ARTHUR J. SUNDLUN, a citizen of the United States, residing at 935 F Street, Northwest, city of Washington, District of Columbia, have invented a new, original, and ornamental Design for a Button or Similar Article, of which the following is a specification, reference being had to the accompanying drawings, forming part thereof.

Fig. 1 is a front elevational view of a button or similar article showing my new design.

Fig. 2 is an edge view of the same.

I claim:

The ornamental design for a button or similar article, as shown.

ARTHUR J. SUNDLUN.
